UNITED STATES PATENT OFFICE

141,529

DESIGN FOR A LOCOMOTIVE

George W. Walker, Pleasant Ridge, Mich., assignor to Bohn Aluminum & Brass Corporation, Detroit, Mich., a corporation

Application August 23, 1943, Serial No. 110,984

Term of patent 3½ years

(Cl. D66—1)

To all whom it may concern:

Be it known that George W. Walker, a citizen of the United States of America, residing at Pleasant Ridge, in the county of Oakland and State of Michigan, has invented a certain new, original, and ornamental Design for Locomotive, of which the following is a specification, reference being had to the accompanying drawing, forming a part thereof, wherein:

Fig. 1 is a perspective view of a locomotive embodying my new design;

Fig. 2 is a plan view thereof;

Fig. 3 is a side elevational view thereof; and
Fig. 4 is a rear elevational view thereof.

I claim:

The ornamental design for a locomotive, substantially as shown.

GEORGE W. WALKER.
